UNITED STATES PATENT OFFICE.

WILLIAM HENRY BARTEN, OF GORDON, NEBRASKA.

BALING-MACHINE.

1,159,639.

Specification of Letters Patent.

Patented Nov. 9, 1915.

Application filed August 18, 1914. Serial No. 857,369.

To all whom it may concern:

Be it known that I, WILLIAM HENRY BARTEN, a citizen of the United States, residing at Gordon, in the county of Sheridan and 5 State of Nebraska, have invented a new and useful Baling-Machine, of which the following is a specification.

The objects of this invention are to provide means for forming articles like empty 10 Portland cement bags, empty house-builders' plaster bags, rags, paper, cotton, straw, etc., into bales and bundles, encircle same with any suitable means as one or more bands of wire, rope, string, cable, belt, chain 15 and the like, which-ever is at hand, least expensive, and best adapted for the particular bale and purpose. Also to form bales by the material being baled containing some adhesive like substance as glue, cement, or the 20 like that will hold the materials baled together without bands encircling the completed bale. And to accomplish the above named objects with the least possible exertion of power, with the greatest possible 25 speed, in the most desirable manner and at the smallest possible cost for operation, material, and the cost of construction of the machine and its repairs. I attain these objects by the mechanism illustrated in the accompanying drawing and set forth in this 30 specification.

In the accompanying drawing Figure 1 is a perspective view of the machine. Fig. 2 is a perspective view of the machine containing a bale formed, compressed and tied, ready to be removed from the machine.

Similar letters refer to similar parts throughout the several views.

The table or plate L supports the shaft 40 boxes I I, the pegs C C C, and the pegs E E E. In the shaft boxes I I turns the shaft J by means of a crank B'. When the machine is very large a long lever may be used instead of the crank B'. And in some 45 instances a pulley may be used in place of the crank B' for using power from a steam or gas engine. In some instances the pegs C C C, or a fence need not be used. The bale then rests against the shaft J which 50 acts as a fence as well as winds the bands B B B compressing the bale.

The operation of the machine is as follows: Wires or bands B B B, as many as are desired, are placed on the table of the

machine, as shown in Fig. 1. An end of 55 each wire is fastened near the shaft J, or even to the shaft J if desired, but preferably to one of the pegs E E E. The material to be baled is then placed at A, across the wires B B B and against the pegs C C C. 60 The ends of the wires B B B are next drawn over the material to be baled, and fastened to the shaft J, preferably passed into the openings D D D of the shaft. Turning the crank B' winds the wires B B B on to the 65 shaft J, moving, rolling, forming and compressing the material of the bale very densely together into a cylinder like roll. The mechanical principle being similar to the power obtained with a timberman's rolling hitch in rolling logs. Some materials baled do not roll together as well as others but are compressed closely together by the bands B B B when the crank B' is turned. When the bottom wire passes peg C on one 70 side the same wire coming over the material baled passes peg C on the opposite side. After the bale is compressed as much as desired, lever P is drawn over the crank B' to hold said crank from turning back. Peg C 75 is next drawn up out of its socket and the wires passing this peg are twisted together with this same peg. The twisted wire is then cut off any where as at or near H and the bale removed from the machine. And 80 the peg C is then put back into its socket. The wires may both pass on one side of peg C and be twisted together with a nail like key G. A rope, cable, chain, belt, etc., may be used instead of wires B B B for compressing 85 the bale and then a different band might be tied around the bale. It is also possible to omit a number of the parts of the machine and yet have enough of the machine left to form material into bales. For instance the 90 shaft J and the bands B might be used by placing the bands B around the material, fasten both ends of the bands to the shaft J, turn the shaft winding on it the bands until the bale is compressed as much as desired. 100

I claim:

1. A baling machine for making bales having a suitable base like table, a shaft mounted on said table, a means for rotating said shaft, a fence like means retarding the 105 movement of the material baled, means for holding bands operatively near said shaft, means for connecting said bands with said

shaft, and means for joining the ends of the bands encircling the bale.

2. A bale forming, pressing and tying machine having a suitable base, a winding device, a support for material to be baled, a support holding an end of the band compressing the bale, a means for connecting said band with said winding device and

means for twisting together the ends of the band that encircles the bale.

In testimony whereof I affix my signature in the presence of two witnesses.

WILLIAM HENRY BARTEN.
